UNITED STATES PATENT OFFICE

GLEN G. GRISWOLD, OF MADISON, OHIO

DISPLAY CASE

Application filed March 15, 1928. Serial No. 261,988.

The present invention relates broadly to the art of display cases, and more particularly to a portable case especially adapted for the reception and display of articles such, for example, as honey and other sweets which are rendered less attractive and appetizing by the display thereof in the open air.

It is customary in the trade for confectioners, storekeepers and the like, handling commodities of the general character herein contemplated, to display the same both in the comb and in jars, glasses or the like.

The present invention has for one of its objects the provision of a display case adapted to be compactly folded to facilitate shipping, and constructed to provide a readily cleaned, tight enclosure for the reception of certain commodities, and a display rack for the reception of other commodities of the same general type which are not deleteriously affected by free exposure to the air.

Certain related features are described and claimed in my copending application Serial No. 407,875, filed Nov. 18, 1929.

In the accompanying drawings is shown for purposes of illustration only, a preferred form of my invention, it being understood that the drawings do not define the limits of my invention inasmuch as changes in the general contour, appearance and arrangement of the parts and the materials of which they are constructed may be made without departing either from the spirit of the invention or the scope of my broader claims.

In the drawings:—

Figure 1 is a perspective view of a display case constructed in accordance with the present invention;

Figure 2 is a vertical transverse sectional view through the case with the parts in the position illustrated in Figure 1;

Figure 3 is a perspective view of the display case of Figures 1 and 2 with the folding display rack in the position it occupies during shipping;

Figure 4 is a detail perspective view illustrating a portion of the door structure; and

Figure 5 is a detail section in a horizontal plane through one corner of the case.

In carrying out the present invention there

may be provided a display case of any desired size and having any desired capacity, the particular features of construction here illustrated, however, being adapted to cases of relatively small size, adapted to be moved from place to place and positioned at a convenient point on a counter, shelf or the like, affording a clear view to the customer from one side, and access to the salesman from the opposite side.

The display case preferably comprises a base 2, having grooves 3 extending transversely of the upper face thereof adjacent the ends for the reception of end pieces 4. Carried by the end pieces is a top 5 having a construction similar to that of the base and formed with grooves 6 for the reception of the end pieces, whereby a rigid frame is provided.

Formed in the top is a longitudinally extending slot 7, having a width substantially equal to the thickness of a piece of glass 8, which it is desired to utilize as the front of the case. The slot 7 extends in alignment with grooves 9 on the inner faces of the end pieces, and these grooves in turn align with a similar groove 10 in the upper face of the base. By reason of this construction it will be apparent that the piece of glass 8 may be readily dropped into position and firmly held against accidental movement while in this position, the sides of the grooves and slot cooperating with the glass to provide a substantially complete closure for the front of the case.

At one or more desired intermediate points in the case, depending upon the number of shelves which it is desired to provide therein, the end pieces may be formed with transversely extending grooves 11 adapted to slidably receive a piece of glass 12 of a width to lie completely within the case and form a shelf for the display of articles, such as combs of honey.

Carried by the base is a door 13, which is normally urged into closed position by spring hinges 14. In order to form a tight closure for the door, the rear edge of the top and end pieces are formed with rabbets 15 which are preferably provided with a seating and cush-

ioning material 16, adapted to engage the edges of the door during the closing movement and cushion its impact under the force of the spring hinges and at the same time engage it tightly enough to prevent the ingress of dust and other foreign material. The lower edge of the door is sealed by providing a stop strip 17 on the base.

For holding the door 13 in open position to facilitate access to and removal of contents from the case, it is provided with a combined guide and stop strip 18, the slot 19 of which is enlarged at its inner end to provide a recess 20 into which the screw 21 may drop to prevent the door from swinging shut.

Carried by the top of the case is a display rack comprising front and back members 22 and 23 respectively, of generally similar construction and mounting. The front member 22 has inturned ends or wings 24 through which pivotal connecting means 25 extend for securing the front member to the opposite ends of the top adjacent the front edge thereof. The position of the pivotal means 25 is such that the front member may either be swung in its open display position of Figures 1 and 2, or into its closed shipping position of Figure 3.

In like manner, the back member 24 has inturned ends or wings 26, through which extend pivotal fastening means 27 securing the same to the opposite end portions of the top adjacent the rear edge, and so located as to permit the back member to be swung either into its open display position of Figures 1 and 2 or its closed shipping position of Figure 3.

With the parts in display position, there is provided a completely enclosed display space for the reception of jars, glasses, and the like, which may be exposed freely to the air without possibility of contamination of, or injury to, the contents. The front and back members, together with their inturned ends, preclude any possibility of breakage of the displayed articles such as would occur if they were permitted to tip or fall from the top of the case. When in closed position, which they occupy for shipping, they completely close the slot 7 and prevent the possibility of displacement of the glass front 8.

Carried by the back member, and preferably detachably secured thereto, is a receptacle 28 having an open front and top, the side edges 29 of the receptacle being formed with one or more projections 30 adapted to extend through openings 31 in the back member 23 to permit the receptacle to be quickly mounted in position thereon or removed therefrom. This receptacle is adapted for the reception of cartons, boxes, or the like, which are thus maintained in a position readily accessible to the salesman for wrapping either the combs in the display case, or the bottles, jars or glasses from the display rack. The

length of the receptacle is substantially equal to, but slightly less than, the internal length of the display case, whereby the receptacle may be maintained within the case during shipment. It will thus be seen that I have provided a case from which the glass front and shelf may be readily removed for cleaning as found necessary, and which are held against accidental displacement during shipment of the case by the folding display members and the back.

The pivotal connecting means 25 and 27, while they may comprise independent fastenings, preferably comprise opposite ends of a yoke 32, extending continuously therebetween and lying closely adjacent the inturned ends 24 and 26 of the front and back members, whereby these members are protected against springing outwardly during the handling of the case. The lower edges of these inturned ends may be provided with flanges 33 adapted to abut against the under side of the yoke with the parts in display position, as clearly shown in Figure 1, to thereby definitely limit the movement of the display members to open position.

With the display members swung into folded position they lie tightly adjacent the upper surface on the top and are reinforced thereby, thus not only facilitating shipment, but providing a more compact assembly. The receptacle in like manner, while capable of being supported in easily accessible position during the use of the case, may be mounted entirely therein during the shipment. The case, due to its attractive appearance and general construction, serves as an attractive and efficient means for the ready display and handling of commodities of the character herein referred to.

I claim:

1. In a device of the character described, a display case, comprising a frame including a slotted top member, a transparent closure slidable through the slot in said top member into and out of operable position, and a display rack foldable into position to close said slot during shipment of the case.

2. In a device of the character described, a display case, comprising a frame including a slotted top member, a transparent closure slidable through the slot in said top member into and out of operable position, and a display rack foldable into position to close said slot during shipment of the case, said display rack comprising front and back members.

3. In a device of the character described, a display case, comprising a frame including a slotted top member, a transparent closure slidable through the slot in said top member into and out of operable position, and a display rack foldable into position to close said slot during shipment of the case, said display rack comprising front and back members piv-

totally secured to the top member adjacent the opposite edges thereof.

4. In a device of the character described, a display case comprising a frame including a top, a front display member pivotally mounted on said top, a back display member pivotally mounted on said top, said members being adapted to be swung into either open or closed position, and a receptacle removably carried by one of said members.

5. In a device of the character described, a display case comprising a frame including a top, a front display member pivotally mounted on said top, a back display member pivotally mounted on said top, said members being adapted to be swung into either open or closed position, and a receptacle detachably supported by said back member and constructed to lie within the case during shipment.

6. In a device of the character described, a display case comprising a frame including a top, a front display member pivotally mounted on said top, a back display member pivotally mounted on said top, the pivotal mountings for said front and back members comprising opposite ends of a yoke forming a guide for said members during opening movement, and means for limiting the opening movement of said members.

7. In a device of the character described, a display case comprising a frame including a top, a front display member pivotally mounted on said top, a back display member pivotally mounted on said top, the pivotal mountings for said front and back members comprising opposite ends of a yoke forming a guide for said members during opening movement, and means for limiting the opening movement of said members, said means comprising flanges on the lower edges of said members adapted to engage said yoke.

8. In a device of the character described, a frame and a display rack connected therewith by a pivot, the pivot having a stop portion against which a portion of the rack is adapted to lie to assist in maintaining the rack in position, the rack having a portion adapted to lie against said stop portion of the pivot.

9. In a device of the character described, a display case having a closure openable to provide access to the interior of the case, a second closure opposite that first mentioned and bodily removable from the case to permit cleaning, and a display rack foldable against the case for shipment, the rack having means for protecting at least one of said closures.

10. In a device of the character described, a display case and a display rack at the top thereof, such rack comprising oppositely disposed portions pivoted to the case and having wings at their ends, such portions being foldable against the case one within the other.

11. In a device of the character described, a display case, and a display rack thereon hav-

ing oppositely disposed portions foldable against the case in overlapping relationship, such portions having wings at their ends which embrace the case when the rack is folded against it.

In testimony whereof I have hereunto set my hand.

GLEN G. GRISWOLD.
